BY

R. Mann ATTORNEY.

UNITED STATES PATENT OFFICE

134,175

DESIGN FOR AN APPLIQUE EMBLEM OR SIMILAR ARTICLE

Frank John Keil, New York, N. Y.

Application July 25, 1942, Serial No. 107,682

Term of patent 3½ years

To all whom it may concern:

Be it known that I, Frank John Keil, a citizen of the United States of America, residing in New York city, county of Queens, and State of New York, have invented a new, original, and ornamental Design for an Applique Emblem or Similar Article, of which the following is a specification, reference being had to the accompanying drawing, forming part thereof.

Fig. 1 is a plan view of an applique emblem or similar article showing my new design.

Fig. 2 is an edge view thereof.

I claim:

The ornamental design for an applique emblem or similar article, substantially as shown.

FRANK JOHN KEIL.
